CLAIM

The ornamental design for a mouse trap as shown and described.

DESCRIPTION

FIG. 1 is a top, front, right side perspective view of the mouse trap showing my new design;

FIG. 2 is a bottom, rear, left side perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is a perspective view of the mouse trap in a state of use; and,

FIG. 10 is a perspective view of the mouse trap in an open state of use.

The broken lines in the drawings depict portions of the mouse trap that form no part of the claimed design.

1 Claim, 10 Drawing Sheets
